UNITED STATES PATENT OFFICE.

DANIEL L. BRITTON, OF CLEVELAND, OHIO.

RIFLE-GRENADE.

1,316,269.

Specification of Letters Patent. Patented Sept. 16, 1919.

Application filed July 15, 1918. Serial No. 244,855.

To all whom it may concern:

Be it known that I, DANIEL L. BRITTON, a citizen of the United States, residing at c/o The Haddam, 10510 Euclid ave., city of 5 Cleveland, in the county of Cuyahoga and State of Ohio, have invented a new and useful Improvement in Rifle-Grenades, of which the following is a specification, the principle of the invention being herein explained and the best mode in which I have contemplated applying that principle, so as 10 to distinguish it from other inventions.

My invention pertains to a rifle grenade or explosive projectile adapted to be discharged from a suitable container detachably carried at the muzzle of a service rifle.

As developed by the exigencies of the war now waging so-called rifle grenades have assumed a size of about two inches in diameter, are formed with a central bore purposed to come in line with the rifle barrel and to permit the passage of the bullet therethrough. The latter, after passing through the bore, impinged against a device 20 adapted to fire a time fuse usually of seven seconds burning duration which in turn set off a detonator and thus caused the chemical transformation of the explosive charge, usually at about the limit of the effective 25 range of from 200 to 225 yards. The results obtained by the use of rifle grenades, as heretofore constructed, has been very effective for the rather limited range when discharged and exploded precisely as calculated.

In consequence of my observation of the official tests at Government proving fields I became aware, however, of two features 40 which call for improvement. One was a needless limitation of range and the other was an ever present danger of premature explosion. The range was obviously reduced owing to the escape of some of the explosive gases through the central tube of 45 the grenade which inevitably meant a correspondingly reduced effective pressure against the base of the grenade. Owing to impossibility of always having the central tube of the grenade in perfect alignment with the rifle barrel at the moment of 50 firing the cartridge therein, the high velocity bullet sometimes impinged, or at least rubbed against, the inner wall of such tube

and in a number of instances with sufficient violence to cause the grenade to explode prematurely within a few yards of the muzzle of the rifle which with a full war time load would cause most unfortunate and disastrous results.

Accordingly, my invention comprehends 60 the design of a rifle grenade in which the central bore is eliminated and by reason of which blank rifle cartridges are to be employed. This single alteration effects at one and the same time both of the desired improvements so that the likelihood of the 65 premature explosion being caused by the discharged bullet cannot obtain and the full pressure of the discharge gases from the rifle cartridge, reduced only in corresponding 70 proportion to the relative enlargement of the base of the grenade with reference to the caliber of the rifle, can be utilized. I estimate that the range of the grenade when using the same powder charge as that of the 75 present service cartridge can be increased to about 300 yards. Incidentally, a saving is effected in respect to the material of which the bullets are composed, and in respect to the rifle tube through the grenade 80 as heretofore manufactured as well as the necessary machining required to support it in place.

Adverting to the drawings:

Figure I is an elevation of a rifle provided with a discharger tube detachably carried upon the muzzle thereof.

Fig. II is an enlarged view of the muzzle end of a rifle barrel and attached discharger showing a rifle grenade deposited 90 therein.

Fig. III is an elevation of a rifle grenade embodying my invention.

Fig. IV is a mainly vertical section of Fig. III, certain parts appearing in elevation and showing the interior parts in normal position.

Fig. V is a section on line V—V of Fig. IV looking in the direction indicated by the arrows.

Fig. VI is a part elevation and part section of a rifle grenade embodying my invention, showing the position of the parts at the instant of firing.

A rifle having a barrel 1 provided at its 105 muzzle with a foresight 2 carries a rela-

tively enlarged discharger tube 3 adapted to be attached to the barrel 1 by a bayonet joint connection at 4 with the sight 2.

The discharger tube 3 is adapted to 5 close a rifle grenade comprising a hollow body 5 of circular cross-section. Somewhat nearer the base, or rear end of the body 5, the same is provided with a partition 6. The interior surface of the forward portion 10 of the body 5 is fashioned with corrugations 7 so that when the grenade bursts a more or less definite number of pieces are assured. On one side of the slightly tapering forward end or nose the body 5 is provided with a loading plug 8 through which an explosive charge of trinitrotoluol (T. N. T.) is to be inserted. Diametrically opposite the plug 8 is a balancing lug 9.

The center of the nose is fashioned with 20 an opening 10 in line with a similar sized opening 11, formed in the partition 6.0 occupying the holes 10 and 11 with a pressed fit and extending therebetween is a detonator tube 12. Fitted into that end of the 25 detonator tube 12, which is at the partition 6, is a fuse container composed of an outwardly projecting portion 13, an interjacent portion 14 in telescopic connection with the tube 12 and an opposite end 15 of still 30 further reduced diameter. Likewise fitted into the hollowed end of the projecting portion 13 is an explosive cap 16, while occupying the remainder of the fuse container is a time fuse 17 ordinarily designed to burn 35 within a few seconds. The portion 13 of the fuse container is provided with diametrically opposite vent openings 18 in order to favor the ignition of the fuse 17.

A detonator comprises a copper jacket 19 40 having its forward end closed and adapted to contain a detonating charge 20 held in place some distance from the opposite end by means of a retaining cap 21 which is tightly seated within the jacket 19 and 45 which cap when sufficiently heated by the burning of the fuse 17 sets off the charge 20. The rear or unfilled end of the jacket 19 is telescopically fitted between the detonator tube 12 and the forward end 15 of the fuse 50 container. By this arrangement the forward or terminal end of the fuse 17 is brought into close proximity to the detonator, as is clearly shown in Fig. IV. Also insertible through the opening 10 is a rubber 55 tightening cup 22 adapted to serve as a cushion between the closed end of the detonator and the detonator plug 23.

The hollow portion of the grenade body 5 which is located rearwardly of the partition 6 is provided with oppositely disposed 60 vent openings 24. The grenade chamber thus vented is closed near the base of the grenade by a movable forwardly dished striker plate 25 which is formed interiorly with right 65 angularly related and centrally located edges

26. The arrangement of these edges is particularly illustrated in Fig. V and is such as to enable them to impinge against the explosive cap 16 whereby to fire the same. The striker plate 25 is spaced a predetermined distance from the base of the grenade body as a whole by means of an expansion lock ring 27 so that a recess 28 is provided at the base of the grenade body 5 acting as a gas check and serving to cause a circling of the discharged gases from the rifle and thereby assure a more uniform application of pressure over the area of the striker plate 25. It is for the purpose of contributing to such desirable circling of the gases that the rear side of the plate 25 is concaved. A coiled compression spring 29 surrounds the portion 13 of the fuse container and acts normally to hold the striker plate 25 rearwardly against the lock ring 27. In order, however, 25 to still further insure of the spacing of the edges 26 on the striker plate 25 out of contact with the explosive cap 16 so as to serve as a more nearly absolute safeguard against premature explosion, I provide a cotter pin 30 adapted to pass through two pairs of registering openings in the rear end of the body 5 and opposite sides of the striker plate 25. One end of the cotter pin is provided with an enlarged ring 31 by means of 35 which it may be more readily withdrawn.

In rifle grenades heretofore used the detonators were not inserted until just prior to use of the grenade and so far as I am aware this is now being done by the men occupying 100 the trenches. According to my invention the detonator can be seated before the grenades are distributed to the men who are to use them thereby saving time when and where it is a most important object. It is 105 noticed moreover that a rifle grenade, constructed according to my invention, cannot be inserted in the discharger tube until the cotter pin 30 has been withdrawn. This guarantees safety in handling the grenade 110 when not in the rifle and also makes certain that the parts are free to operate when the grenade is inserted in the discharger tube.

While the operation of the rifle grenade hereinbefore described may be obvious the 115 following explanation is furnished. After the cotter pin 30 has been removed the striker plate 25 is nevertheless safely held spaced from the explosive cap 16 owing to the exertion of the spring 29 tending to separate 120 them. Ordinary manipulation is not sufficient to overcome the energy of the spring 29. When the grenade has been inserted in the discharger 3 and a blank cartridge is fired in the rifle the discharge gases will impinge against the striker plate 25 and the pressure established thereagainst will overcome the action of the spring 29 and cause the edges 26 sharply to impinge against the explosive cap 16 thereby firing the fuse 17 13

at the moment that the grenade is propelled from the discharger tube. Inasmuch as the entire pressure possible to be distributed over the area of the striker plate 25 can be utilized an added range will be attained.

I claim:

1. A rifle grenade adapted to be propelled by the explosive gases issuing from the muzzle of a rifle and having a hollow rear 10 end, a striker plate movably fitted to, and wholly confined by said rear end, said plate being concaved in a forward direction whereby to cause a circling of and more uniform application of pressure by the dis- 15 charge gases.

2. A hollow rifle grenade adapted to be propelled in its entirety and including at its rear an interiorly positioned striker plate adapted to partition off the rear portion of 20 said grenade and to form in conjunction therewith a rearwardly presented recess for the purpose specified.

3. A rifle grenade comprising a hollow casing, provided with a closing base wholly 25 confined by and adapted for movement within said casing and means for holding said base in a given position.

4. A rifle grenade comprising a hollow casing having its rear end open, a striker 30 plate movably fitted therein, and distinct means for limiting the movement of said plate in opposite directions respectively.

5. A rifle grenade comprising a hollow casing, a base movably supported therein, a 35 spring acting to hold said base in its rear-most position and additional means for locking said base in such position.

6. A rifle grenade adapted to be propelled from a discharger of given bore comprising 40 a hollow casing adapted to fit said bore and containing an explosive charge, a detonator, a time fuse and an explosive cap, a striker plate movably fitted between the walls of said casing so as to closely approach the size 45 thereof, said plate provided interiorly with a projection adapted to engage said explosive cap and an interiorly positioned spring normally acting to hold said plate and cap apart.

50 7. A rifle grenade comprising a hollow casing, an explosive charge therein, a movable striker plate fitted in its entirety to the interior wall of said casing and a device for setting off said explosive charge and including elements adapted to be brought into engagement upon actuation of said base member.

8. A rifle grenade comprising a hollow casing of circular cross section and having 60 its entire rear end open, an explosive charge in said casing, a movable striker plate fitted in such end, means for limiting the movement of said plate toward the end of said casing, a device for setting off said explosive charge, including elements adapted

to be brought into engagement upon actuation of said base member away from such casing end and means for locking said base member in a given position.

9. A rifle grenade comprising a hollow 70 casing provided with a partition, a striker plate closing the rear end of said grenade and movable toward and away from said partition, and means normally coacting to hold said plate a predetermined distance 75 from said partition for the purpose specified.

10. A rifle grenade comprising a hollow casing provided with a partition, a striker plate closing the rear end of said grenade 80 and movable toward and away from said partition, explosive agencies within said casing including an ignitable element between said partition and plate, means normally coacting to hold said plate a predetermined distance from said partition said plate being adapted to engage and fire said element, and a safety device for fixing said plate in a given position.

11. A rifle grenade comprising a hollow 90 casing provided with a partition, a striker plate closing the rear end of said grenade and movable toward and away from said partition, explosive agencies within said casing including an explosive cap between said 95 partition and plate and some distance from said partition, a spring normally coacting to hold said plate a predetermined distance from said cap, said plate being adapted to engage and fire said cap while leaving a free 100 space behind said partition to aid combustion.

12. A hollow rifle grenade formed intermediately of its ends with a partition and carrying at its rear end an internally projecting part, an explosive cap carried by the side of said partition nearest such part, a striker plate movable between said cap and part and means for holding the latter 105 against said part.

13. A hollow rifle grenade carrying a partition and in its rear end a movable striker plate, a spring acting to press said plate from said partition, explosive means including parts upon said partition and plate adapted to engage, and a cotter pin for locking said plate out of such engaging position.

14. A rifle grenade comprising a hollow casing, a partition thereacross having an opening, a fuse container projecting through said opening, a striker plate movably carried inside of the rear end of said casing and provided interiorly thereof with a firing projection and agencies including a time fuse in said container and an explosive charge forwardly of said partition adapted to be fired by the movement of said base.

15. A rifle grenade comprising a hollow casing having a partition, a striker plate movably carried inside of said casing and

at the rear end thereof, said plate being provided interiorly of said casing with a firing projection, a fuse container centrally supported by said partition and projecting rearwardly thereof, and agencies including a time fuse in said container, explosive charge forwardly of said partition and explosive cap at such projecting end of said container, said cap adapted to be fired by 10 the engagement therewith of said projection whereby to light said fuse and after a predetermined time interval to set off said explosive charge, said projecting end of said fuse container being fashioned with vents 15 whereby to favor free combustion in the space afforded between said partition and

plate at the time of firing said cap and fuse.

16. A rifle grenade having a hollow rear end, and including a striker plate completely 20 confined by and bodily movable in an axial direction within said hollow rear end whereby a recess is provided serving to cause a circling of the discharged gases.

17. A rifle grenade comprising a hollow 25 casing, and a striker plate across its rear end, said plate being bodily movable in its entirety within said casing and a predetermined distance away from the rear end thereof for the purpose specified. 30

Signed by me, this 9th day of July, 1918.
DANIEL L. BRITTEN.
